(57) **CLAIM**

The ornamental design for a limiter ring, as shown and described.

DESCRIPTION

FIG. 1 is a front left perspective view of a ring showing my new design;

FIG. 2 is a front elevation view thereof;

FIG. 3 is a top plan view thereof, with the bottom view, left-side view, and right-side view being identical thereto; and,

FIG. 4 is a cross-sectional view along line 4-4 of FIG. 2.
